(57) **CLAIM**

The ornamental design for a pocketed spring comfort layer, as shown and described.

DESCRIPTION

FIG. 1 is a top perspective view of a pocketed spring comfort layer illustrating our new design;

FIG. 2 is a top perspective view thereof, but shown without the environmental subject matter;

FIG. 3 is a front view thereof;

FIG. 4 is a rear view thereof;

FIG. 5 is a right view thereof;

FIG. 6 is a left view thereof;

FIG. 7 is a top view thereof, the bottom view being identical;

FIG. 8 is a top perspective view of another embodiment of the pocketed spring comfort layer;

FIG. 9 is a top perspective view thereof, but shown without the environmental subject matter;

FIG. 10 is a front view thereof;

FIG. 11 is a rear view thereof;

FIG. 12 is a right view thereof;

FIG. 13 is a left view thereof;

FIG. 14 is a top view thereof, the bottom view being identical;

FIG. 15 is a top perspective view of another embodiment of the pocketed spring comfort layer;

FIG. 16 is a top perspective view thereof, but shown without the environmental subject matter;

FIG. 17 is a front view thereof;

FIG. 18 is a rear view thereof;

FIG. 19 is a right view thereof;

FIG. 20 is a left view thereof;

FIG. 21 is a top view thereof, the bottom view being identical;

FIG. 22 is a top perspective view of another embodiment of the pocketed spring comfort layer;

FIG. 23 is a top perspective view thereof, but shown without the environmental subject matter;

FIG. 24 is a front view thereof;

(Continued)

FIG. 25 is a rear view thereof;
 FIG. 26 is a right view thereof;
 FIG. 27 is a left view thereof; and,
 FIG. 28 is a top view thereof, the bottom view being identical.
 Any elements shown in broken lines form no part of the claimed invention and are instead included to show environmental aspects of the claimed invention.
